UNITED STATES PATENT OFFICE

CHARLES M. RICHARDSON AND VIRGIL H. BODLE, OF AKRON, OHIO, ASSIGNEES TO THE B. F. GOODRICH COMPANY, OF NEW YORK, N. Y., A CORPORATION OF NEW YORK

APPARATUS FOR SOLING AND PRESSING FOOTWEAR

Application filed July 7, 1927. Serial No. 204,016.

This invention relates to the manufacture of footwear and especially rubber-soled shoes such as overshoes, rubbers, tennis shoes and the like.

5 Our chief objects are to provide improved apparatus for pressing a rubber sole in place upon the shoe; to provide in an improved manner for pressing the sole and turning its margin onto the upper in the same operation; 10 to provide for first pressing the sole and thereafter pressing the rest of the shoe in the same operation; to provide a machine adapted to operate upon shoes of many different sizes with but little adjustment or substitution of parts; to provide cyclic and largely 15 automatic operation; to provide for safety of the operator; and to provide numerous, more detailed advantages which will be manifest.

20 Of the accompanying drawings:

Fig. 1 is an elevation of a machine embodying and adapted to carry out our invention in its preferred form, a part being sectioned and broken away.

25 Fig. 2 is an elevation of the same from the left of Fig. 1, parts being sectioned and broken away, the machine and the work therein being shown at the beginning of the pressing operation.

30 Fig. 3 is a vertical section of the work and a portion of the machine in the vicinity thereof, representing a later stage of operation than that of Fig. 2.

Fig. 4 is a section on line 4—4 of Fig. 1.

35 Fig. 5 is a fragmentary elevation of parts of the machine including an inflatable presser-head and parts of actuating means for presenting it to and removing it from co-operating parts of the machine, the head being shown in pressing position.

Fig. 6 is a similar view showing other parts of the head-actuating means.

45 Referring to the drawings, the machine comprises a frame 10 having mounted in the top thereof a fluid-pressure pot 11 in which is mounted a last-support 12 adapted to receive the shank of a last 13 having an overshoe 14 thereon and to support the same for the pressing operation.

50 The last-support 12 is secured upon the

upper end of a supporting and adjusting screw 15 which is threaded through a quill 16 rotatably mounted in an apertured boss constituting a part of the floor of the fluid-pressure pot 11. Secured upon the lower end 55 of the quill 16, outside of the pot, is a beveled gear 17 (Figs. 1 and 2) which is meshed with a beveled gear 18 secured upon a shaft 19 which extends to the front of the machine and is there provided with a hand wheel 20 whereby the quill 16 may be rotated to raise or lower the last-support 12 within the pot. 60

A cup-shaped lip gasket 21 (Figs. 2 and 3) having its floor apertured to accommodate the screw 15 is mounted upon the said screw 65 and is clamped in sealed relation against the under face of the last-support 12 by means of a washer 22 and a nut 23 mounted upon the said screw, the washer 22 being so fitted against the rear wall of the pot as to 70 permit the last-support to slide vertically but to prevent the last-support from rotating in the vertical adjustment thereof by rotation of the quill 16. The gasket 21 is adapted to seal about the upper of the overshoe and thus to seal against the last when a fluid pressure is built up within the pot 11, and the last is of the usual vented type and is adapted 75 to be vented during the pressing operation through an aperture 24 extending 80 through the last-support 12 and screw 15 to the outer atmosphere.

The pot 11 is held in position upon the frame 10 by dowel pins such as the pins 25, 85 25 and a spacer ring 26 apertured to accommodate the dowels 25 is interposed between the margin of the pot and the frame 10, the construction being such that rings 26 of different thickness may be substituted for each other to support the pot at different elevations for different sizes or types of overshoes. 90

Surrounding the upper margin of the lip gasket 21 is an annular plate 27 having its outer margin set in a rabbet formed in the upper face of the marginal portion of the pot 11, the plate being provided on its upper and inner surfaces with a rubber surface-member 28 adapted to contact the overshoe 14 without damage to the latter. The plate 95 27 with its rubber facing 28 is adapted to 100

afford a stop for a sole pressing diaphragm, the said plate extending entirely about the overshoe at a substantial distance from the sole of the latter but in close proximity to the adjacent surface of the overshoe, so that a diaphragm distended by fluid pressure into the angle formed by the plate and the overshoe will not be required of its own strength to bridge such a gap between the two as to be subjected to excessive strain by the fluid pressure. The plate 27 is shaped for its rubber facing 28 to be contacted by the upper toe portion of the overshoe for the support of the latter while the shank of the last rests upon the last-support 12, the last-support being in proper vertical adjustment, and at the rear the plate 27 is so formed as to stand close to the substantially vertical rear surface of the overshoe, the construction being such that the plate 27 will serve as a closely surrounding stop for the diaphragm with respect to overshoes of a considerable number of sizes, the last-support being properly adjusted for the different sized overshoes.

An upper presser-head adapted to coact with the lower pressing structure just described comprises an inverted fluid pressure pot 29 having an elastic diaphragm 30 mounted in the manner of a drum head upon the margin of its mouth, the margin of the diaphragm 30 being clamped to the margin of the pot 29 by means of an annular clamping plate 31 and screw bolts 32, 32, the diaphragm being adapted to be held under tension in an upwardly flexed and stretched condition by contact with the sole 33 of the overshoe when the upper presser-head is in pressing position over the lower presser-head. The upper head is so formed that the clamping plate 31 stands in close proximity to the margin of the lower pot 11 when the upper head is in pressing position, so as to avoid such a gap between the two as would subject the diaphragm 30 to excessive local strain in the region where it bridges the space between the two, when the diaphragm is forced to the position in which it is shown in Fig. 3 by pressure fluid conducted into the space between the upper pot 29 and the said diaphragm.

For mounting and removing the upper presser-head the pot 29 has secured to its respective sides downwardly extending arms 34, 34 which at their lower ends are pinned upon the respective ends of a rock-shaft 35 journaled in a pair of blocks 36, 36 which are mounted for vertical sliding movement in guide-ways such as the guide-way 37 (Fig. 1) formed in the respective side members of the frame, the pot 29 being adapted to be removed from the pot 11 by being first lifted vertically, the blocks 36 sliding in their guide-ways, and then to be tilted to a position at the rear of the lower pot, as shown by the broken lines in Fig. 6, and to be remounted

over the lower pot by reverse movements.

The means for lifting the shaft 35 and thereby lifting the pot 29 comprises a pair of toggle arms 38, 38 rotatably mounted upon the shaft 35 between the respective arms 34 and the machine frame, each toggle arm 38 being hinged to a toggle arm 39 secured upon a stub shaft 40 mounted in the respective sides of the machine frame and each provided within the frame with an actuating arm 41 connected by an adjustable link 42 with an arm 43 keyed upon a rock-shaft 44 mounted in the machine frame. The right-hand arm 43 as viewed in Fig. 2 has mounted thereon a cam roller 45 extending into a cam groove 46 formed in a cam disk 47 which is secured upon a main drive shaft 48, the cam disk 47 thus being adapted to straighten the toggles 38—39, 38—39 to lower the upper presser-head and to break the toggles to raise the said head during each revolution of the shaft 48.

For tilting the upper head from its inclined broken line position of Fig. 6 to its vertical broken line position of Fig. 6 and to tilt it back again to the inclined position in each cycle of operation, in timed relation to the lifting and lowering of the head by the toggles, the rock-shaft 35 has keyed thereon an arm 49 provided at its outer end with a cam stud 50 extending into a cam slot 51 (Fig. 6) formed in one arm of a bell crank lever 52 which is fulcrumed upon a shaft 53 and has upon the outer end of its other arm a cam roller 54 mounted in a cam groove 55 formed in a cam disk 56 which is secured upon the drive shaft 48.

The main drive shaft 48 has secured upon one end thereof, within a gear housing 57 screw bolted to the outer face of the machine frame, a clutch structure (see Fig. 4) comprising a flanged bushing 58 and a collar 59 secured thereon and defining therewith an annular channel 60 which accommodates an arcuate cam 61. Mounted in an aperture formed in the flanged bushing 58 is a clutch pin 62 having an obliquely faced head 63 projecting radially of the structure into the channel 60 for coaction with the arcuate cam 61 for disengaging the pin 62 from the hub structure of a worm gear 64 which is rotatably mounted upon the shaft 48 and meshed with a worm 65 having drive connection with a motor 66 (Figs. 1 and 2). The collar 59 is formed with a slot 67 to accommodate the head 63 of the clutch pin 62 and give the pin structure a wide bearing, and a compression spring 68 mounted in a slot formed in the flanged bushing 58 is interposed between the pin 62 and a cap plate 69 secured upon the end of the shaft 48, for urging the pin 62 into engagement with the hub structure of the worm gear 64 when the head 63 of the pin passes out of engagement with the arcuate cam member 61.

For engagement with the pin 62 the hub structure of the worm gear 64 is formed with at least one pin receiving recess defined by the hub of the worm gear and a flanged collar 70 secured thereon.

The arcuate cam 61 is secured upon a pin 71 which is slidably mounted in guide apertures formed in the gear housing 57, the pin being urged upwardly to hold the cam member in declutching position by a compression spring 72 interposed between a washer 74 abutting a shoulder formed on the pin and an apertured lug 73 projecting from the gear casing and having the pin 71 mounted therein.

For pulling the pin 71 downward to release the clutch pin 62 and permit the latter to engage the hub structure of the worm gear 64, the lower end of the pin 71 has pin-and-slot hinge connection with a lever 75 fulcrumed on the frame at 76 and having at the outer end of its other arm a radially disposed fork in which is slidably mounted a vertical pull rod 77 provided at its lower end with nuts 78 for lifting the adjacent arm of the lever. The pull rod 77 is mounted at its upper end in an apertured bracket 78 (Fig. 1) secured to the machine frame and a compression spring 79 is interposed between the said bracket and a washer 80 mounted below it upon the pull rod 77, for urging the pull rod downward to a limit imposed by contact of a head 81, secured upon the upper end of the rod, with the upper face of the bracket 78.

For lifting the pull rod 77 to start the machine, the head 81 has journaled therein a pulley 82 occupying the depending loop of a sprocket chain 83 which has its ends secured to respective arms 84, 84 secured upon respective shafts 85, 86 which are journaled in the framing and have at their outer ends respective handles such as the handle 87 projecting to the front of the machine, the construction being such that the operator is required to use both hands, in engagement with the respective handles 87, in order to lift the pull rods 77 to a sufficient height to retract the arcuate cam 61 and thus permit the pin 62 (Fig. 4) to connect the machine with the drive gear 64.

Provision is made for applying a vacuum to the interior of the upper presser-head momentarily at such times as the head is being mounted upon or removed from the work, so that as the diaphragm comes into contact with the sole of the shoe it will be already stretched in its sole contacting portion and consequently will not unduly stretch the sole by binding contact therewith in the forcing downward of the head over the shoe and in the subsequent distending of the diaphragm by fluid pressure. The construction also is such that only a moderate amount of further stretching of the marginal zone of

the diaphragm occurs in forcing it from its position in Fig. 2 to its position in Fig. 3, and such increased tension upon the central part of the diaphragm as to stretch the sole unduly is avoided.

Provision is made for conducting air at high pressure, preferably about 40 pounds to the square inch, into the upper presser-head, back of the diaphragm 30, as soon as the presser-head is in position upon the work, and provision is made for then increasing such pressure, preferably to about 80 pounds to the square inch, while a little more slowly an almost equal pressure is built up in the lower presser-head which comprises the pot 11, the pressure in the upper head continuing to be sufficiently higher than that in the lower head to hold the diaphragm 30 distended to the position in which it is shown in Fig. 3 and thus to provide a seal of the diaphragm against the rubber facing member 28 of the plate 27 to prevent the escape of air from the pot 11.

For providing the series of pressure conditions just described a pipe 88 leads from a source of compressed air at 40 pounds pressure, through a cam actuated valve 89 and a check valve 90 (Fig. 1) to a flexible pipe 91 communicating with the chamber of the upper presser-head, the flexible pipe 91 also being in constant communication through a pipe 92 with a chamber 93 (Fig. 4) formed in a valve casing 94 (Figs. 1 and 4) secured to the machine frame. A pipe 95 leads from a source of air at 80 pounds pressure to a chamber 96 formed in the valve casing 94, which chamber 96 has communication through a poppet valve 97 with the chamber 93 and through a poppet valve 98 with a chamber 99 from which a pipe 100 leads to the pot 11 of the lower presser-head. The lower presser-head is adapted to be put in communication through the chamber 99 and a poppet valve 101 with an exhaust pipe 102 opening to the atmosphere. The upper presser-head is adapted to be put in communication through the chamber 92 and a poppet valve 103 with an exhaust pipe 104 opening to the atmosphere. For applying suction to the upper presser-head, the high pressure air pipe 95 is adapted to be put in communication through the chamber 96 and a poppet valve 105 with an ejector pipe 106 having a nozzle 107 mounted in the exhaust pipe 104 and adapted therewith to constitute an ejector.

For opening and closing the several poppet valves in proper timed relation to produce the described series of pressure conditions each valve is urged toward its seat by a compression spring, as shown clearly in Fig. 4, and the stems of the several valves project downwardly from the valve casing and abut respective cam levers 108, 108 which are provided with cam rollers 108^a, 108^a adapted to

coact with a series of cams 101^a, 98^a, 97^a, 103^a and 105^a secured upon a cam shaft 109 which has drive connection through a sprocket chain 110 with the main drive shaft 48.

The several cams are so formed and have such angular relation that in their rotation, beginning with the tilting of the upper presser-head into vertical position over the work, the valves all being closed at the beginning of this movement, the valves 105 and 103 are first opened, the valve 105 permitting high pressure air from the pipe 95 to pass through the ejector pipe 106 and thus to cause a suction in the exhaust pipe 104 and consequently in the upper presser-head, the upper presser-head at that time being in communication with its exhaust pipe 104 through the flexible pipe 91, the pipe 92, the chamber 93 and the valve 103, and a cam-actuated valve 89 (Fig. 1) in the low pressure line 88 being closed; the valves 105 and 103 are then permitted by their cams to close and immediately thereafter the valve 89 in the low pressure pipe 88 is opened by engagement of a cam 111 (Fig. 6) mounted upon the periphery of the cam disk 56 engaging a cam roller 112 mounted upon an actuating lever 113 hinged upon the casing of the valve 89, the air at 40 pounds pressure being applied to the upper presser-head through the check valve 90 and the flexible pipe 91 (Fig. 1), and the valve 97 (Fig. 4) being held closed by the preponderance of air pressure in the chamber 96 as compared with that in the chamber 93. Thereafter but before the cam 111 permits the valve 89 to close, the valve 97 is lifted by its cam, permitting high pressure air from the pipe 95 to pass through the chambers 96 and 93 and the pipes 92 and 91 into the upper head, the check valve 90 (Fig. 1) preventing the high pressure air from flowing into the pipe 88, and immediately thereafter the valve 98 is opened, permitting the high pressure air to flow through the chambers 96 and 99 and the pipe 100 into the pot 11 of the lower presser-head.

As soon as the pressure in the two heads has remained on long enough to thoroughly compress the shoe, rotation of the cam shaft 109 causes the valves 98 and 97 to close, shutting off the air supply to the two heads, and the valves 101, 103 and 105 are opened, exhausting the lower head through the pipe 102 and the upper head through the pipe 104 and momentarily producing a vacuum in the upper head through the action of the ejector comprising the pipes 104 and 106.

Gauges 114, 115 may be provided for indicating the pressures contained in the two head.

The motor 66 is preferably provided with a solenoid brake 116 adapted to be actuated whenever the current is cut off, and in addition to the usual push button starting and stopping switches we preferably provide an

emergency stopping switch, shown in Fig. 1, having a switch-opening lever 117 backed by a spring 118 adapted to hold it in circuit-closing position and provided with a cam roller 119 associated with an arm 120 secured to a shaft 121 provided with an actuating frame 122 adapted readily to be engaged either by the hand or by the body of the operator to open the circuit and thereby stop the current to the motor and simultaneously actuate the brake 116.

In the operation of the machine, the drive-gear 64 being continuously driven by the motor 66, and the upper head being in the inclined dotted line position of Fig. 6 at the beginning of the operation, the last 13 with the overshoe 14 thereon and with the sole 33 in flat form lightly pressed against the body of the shoe and projecting beyond the latter around its margin, is mounted in the gasket 21 and upon the last-support 12 and plate 27. Both the handles 87 are then depressed by the operator, which requires the use of both of his hands for the sake of safety, and in consequence the pin 62 is permitted to engage with the hub structure of the rotating drive gear 64 by the downward withdrawal of the arcuate cam member 61, the construction being such that the shaft 48 will then be driven through one complete revolution and then stopped by withdrawal of the clutch pin 62 through the coaction of its head 63 with the cam member 61.

In this revolution of the shaft 48 the upper head is first swung into position over the lower head by action of the bell crank lever 52 (Fig. 6) and then lowered into position about the lower head by action of the levers 43, links 42, arms 41 and toggles 38-39.

As the initial pressure is applied within the upper head, forcing the diaphragm 30 to its position as shown in Fig. 3, the margin of the sole 33 is folded on to the side faces of the overshoe and firmly pressed in place and the diaphragm 30 also presses the upper against the last in a zone extending about the overshoe adjacent the latter's sole. The pressure upon the sole and upon the said zone is then increased by increase of the pressure in the upper head and concurrently the rest of the overshoe is pressed and compacted by the admission of air to the pot 11 of the lower head, the gasket 21 sealing against the overshoe about the shank of the last, the distorted diaphragm 30 preventing escape of air from the lower head. Air entrapped between the overshoe and the last is vented through the aperture 24 in the last-support 12 and the screw 15.

When the shoe has been adequately pressed, the continuing rotation of the shaft 48 causes the heads to be vented and the upper head sufficiently evacuated to reduce or eliminate the strain of the diaphragm 30 upon the sole of the overshoe, and the upper

head to be lifted and tilted back to the inclined broken line position of Fig. 6, whereupon the engagement of the head 63 of the clutch pin 62 with the cam member 61 causes the clutch pin to be retracted and stops the machine. This completes the cycle of operation, which is then repeated upon successive overshoes.

Various modifications are possible within 10 the scope of our invention as defined in the appended claims.

We claim:

1. Apparatus for soling and pressing an article of footwear, the said apparatus comprising means for supporting a last with an upper and a sole thereon, a flexible diaphragm, means for applying a pressure fluid against said diaphragm on one side thereof to press it against the sole, fluid-confining 20 means which with the other side of the diaphragm and with the upper defines a pressure-fluid chamber for applying pressure-fluid locally to the upper in direct contact therewith, the said fluid-confining means comprising a lip-gasket member adapted to seal against the upper about the mouth thereof.

2. Apparatus for pressing footwear, the said apparatus comprising a last, a fluid-backed, elastic diaphragm, means for forcing one of the same toward the other to press a sole on the last by contact of the diaphragm with the sole, a rigid member surrounding the last at a substantial distance from the sole thereof and presented to the toe portion of the last for limiting the stretch of the diaphragm, the said rigid member being so close to the last at all points about the same as alone to prevent so large a baying of the 30 diaphragm between the last and the member as to result in undue strain of the diaphragm by the fluid by which it is backed, and a member adjustable with relation to the member surrounding the last and so constructed and 40 arranged as to engage the shank of the last, the two said members being adapted to support lasts of different sizes with their sole faces in approximately the same position with relation to the diaphragm.

3. Apparatus for pressing an article of footwear, the said apparatus comprising means for supporting a last, a presser-head including a fluid-backed diaphragm, and means for relatively swinging said head to and from a position of alignment with the last-supporting means and for relatively moving it rectilinearly from said position toward the last-supporting means and from the last-supporting means to said position toward the last-supporting means and from the last-supporting means to said position.

4. Apparatus as defined in claim 3 including means for varying the pressure of the fluid by which the diaphragm is backed by conducting fluid to and from the presser-head.

5. Apparatus for pressing an article of

footwear, the said apparatus comprising means for supporting a last, a presser-head including a fluid-backed diaphragm, means for conducting pressure fluid to said head to distend said diaphragm and means for applying suction to said head to stress the diaphragm in the opposite direction.

6. Apparatus for pressing an article of footwear, the said apparatus comprising means for supporting a last, a presser-head including a fluid-backed diaphragm, means for relatively swinging said head to and from a position of alignment with the last-supporting means and for relatively moving it rectilinearly from said position toward the last-supporting means and from the last-supporting means to said position, means for conducting pressure fluid to said presser-head to distend said diaphragm, and means for applying suction to said head to stress the diaphragm in the opposite direction.

7. Apparatus for pressing an article of footwear, the said apparatus comprising means for supporting a last, a presser-head including a fluid-backed diaphragm, and means for relatively swinging said head to and from a position of alignment with the last-supporting means and for relatively moving it rectilinearly from said position toward the last-supporting means and from the last-supporting means to said position, the head-moving means comprising an actuating member mounted to slide toward and from the last-supporting means in the direction of the rectilinear movement of the presser-head and an arm projecting from the head and pivoted to the said member for the angular movement of the head.

8. Apparatus as defined in claim 7 including a toggle for moving the actuating member and means for actuating the toggle and swinging the head in determinate time relation.

9. Apparatus for pressing an article of footwear, the said apparatus comprising two presser-heads each adapted to apply fluid pressure locally to the article, means for bringing the said heads together upon the article, means for conducting pressure fluid to and from each of the heads, driving means so constructed and arranged as to actuate the several aforesaid means in an automatic, cyclic operation including the bringing of the heads together, the conducting of pressure fluid into the heads, the venting of the pressure fluid therefrom, and the separation of the heads, and means actuated automatically by the driving means in the cyclic operation for applying suction to one of the heads.

10. Apparatus for pressing an article of rubber footwear comprising a pressure-fluid pot, a last-support therein having a stem projecting through a wall of the pot to the exterior thereof, means for securing the stem in different adjusted positions in said wall,

the said last-support and its stem being apertured to vent to the exterior of the pot a last mounted on said last-support, and a lip gasket mounted upon the last-support and 5 adapted to seal against a last mounted on the last-support.

11. Apparatus for pressing an article of footwear, the said apparatus comprising a presser-head, elastic, fluid-backed diaphragm 10 mounted thereon, means for conducting pressure fluid into the head to distend the diaphragm, and means for applying suction to the head to stress the diaphragm in the opposite direction.

15 In witness whereof we have hereunto set our hands this 1st day of July, 1927.

CHARLES M. RICHARDSON.
